UNITED STATES PATENT OFFICE.

GEORGE FRANKLYN MATTESON, OF ROCKY HILL, CONNECTICUT, ASSIGNOR TO THE FULLER BRUSH COMPANY, OF HARTFORD, CONNECTICUT, A CORPORATION OF CONNECTICUT.

WIRE-BENDING MACHINE.

Application filed May 2, 1925. Serial No. 27,576.

My invention relates to that class of machines employed for bending wire into certain predetermined forms, and an object of my invention, among others, is to provide a machine of this class of simple construction that will impart intricate forms to the wire structures in a particularly efficient manner.

One form of machine embodying my invention and in the construction and use of which the objects herein set out, as well as others, may be attained, is illustrated in the accompanying drawings, in which—

Figure 1 is a view in side elevation of a wire bending machine embodying my invention.

Figure 2 is an end view of the same.

Figure 3 is a top view.

Figure 4 is a detail view, scale enlarged, in horizontal section on a plane denoted by the dotted line 4—4 of Figure 8.

Figure 5 is a view in section on a plane denoted by the dotted line 5—5 of Figure 8.

Figure 6 is a detail view illustrating the construction and operation of the bending members and illustrating one step in the bending operation.

Figure 7 is a similar diagrammatic view illustrating a further step in the bending operation.

Figure 8 is a view in vertical section on a plane denoted by the dotted line 8—8 of Figure 4.

Figure 9 is a view in vertical section on a plane denoted by the dotted line 9—9 of Figure 4.

My invention is not limited in its use to a machine for bending wire for any specific purpose, yet as I have found it especially applicable and have, in fact, devised it for the purpose of bending wire structures comprising frames for mops and similar cleaning utensils I have selected such for the purpose of illustration of my invention in the drawings herein in which the frame of my improved machine as illustrated is composed of side parts 10 that may be joined by any suitable cross or tie bars 11 disposed as may be desired to properly strengthen the frame as a whole.

Supports 12 rise from the top edges of each of the side parts 10 and a housing 13 for mechanism for operating the main benders extends between and is secured to said side parts, and

as shown in Figure 3 of the drawings, said housing extending over the upper part of the frame to provide a space in which main and end benders are secured, the articles to be bent being passed into this space for engagement with said benders.

The main bending mechanism comprises intermeshing gears 14—15 rotatably mounted on studs depending from the top of the housing, said gears each having a slot 16 to receive a shiftable block 17 borne on an actuating arm 18 and loosely connected therewith as by means of a stud 19 projecting from the arm into the block, and as shown in Figure 8 of the drawings. The arms 18 are each secured to an actuating shaft 20 rotatably mounted in a block 21 slidable in a slot 22 in the bottom of the housing 13. A bending pinion 23 is secured to each of the shafts 20 in said housing. Bending arms 24 are secured to the ends of said shafts outside of the housing, these bending arms being located in the space between the bottom of the housing and the top of the frame. Each pinion 23 meshes with a rack 25 secured to the bottom of the housing on the inside thereof, and as shown in Figures 4 and 9 of the drawings. The end of each bending arm constitutes a former and the lower side of each arm constitutes a sort of a rib 26, spaced at one end from a former stud 27, and against which rib the structures rest during the bending operation, said stud having its axis coincident with the axis of the shaft 20 to which the arm is secured.

Placers and end benders 28 are secured each to the upper end of a shaft 29, said shafts being mounted in a cross piece 30 extending between and secured to the side parts 10 below the housing 13 and as shown in Figure 2.

These benders each have a bending nose 31 and a positioning pin 32 spaced apart for the reception of the ends 33 of the structures—as a mop 34—to be bent and as illustrated in Figures 8 and 9 of the drawings. The pins 32 are movably mounted in sockets in the bender and are normally forced upwardly as by means of springs and these pins underlie the ends of the ribs 26 when the latter are in their normal positions of rest.

End bending pinions 35 are secured to the shafts 29 within recesses formed in the cross piece 30 and closed as by means of covers 36

secured in place in any suitable manner, as by means of screws, said shafts having bearings formed by said covers and the main part of the cross piece 30. End bending racks 37 are slidably mounted in guide grooves in extensions 38 comprising a portion of the cross piece 30, and as shown in Figure 5, the end bending mechanism comprising the parts just described being located in these extensions, and said racks being in mesh with the end bending pinions 35.

The shafts 29 are vertically movable for the purpose of placing the structure being operated upon within the spaces between the former studs 27 and ribs 26, in which movements the pins 32 are forced downwardly into their sockets in order to permit such movement of the end benders.

The gears 14 and 15 have oscillating movement imparted to them by means of a rack 39 mounted for sliding movement in a way or groove in a side wall of the housing 13, and as shown in Figure 4. This rack is actuated by means of a bending lever 40 pivotally mounted on a shaft 45 and pivotally connected with the rack at one end and in operative engagement with a bending cam 41 at its opposite end, said cam being secured to a cam and driving shaft 42 mounted in the side parts 10, said cam 41 being shaped to impart timely reciprocating movement to the rack to effect the operations hereinafter set forth.

The rack bars 37 are each pivotally connected with end bending arms 43—44 secured to the rock shaft 45 mounted in the side parts 10, the arm 43 being extended to engage with an end bending cam 46. The levers 40 and 43 are engaged within cam grooves in the cams, whereby positive movement is imparted to the levers in both directions. Vertical reciprocating movement of the shafts 29 is effected by means of placing arms 47 secured to a placing shaft 48 mounted in bearings in brackets 49 secured to the cross piece 30, and as shown in Figures 2 and 9 of the drawings. A placing lever 50 is secured to the shaft 48 with its end in engagement with the periphery of the cam 41 that is depressed for actuation of the lever 50 to impart timely reciprocating movement to the shafts 29. An ejector 51 is secured to an ejector shaft 52 mounted in a bracket 53 secured to the housing, and as shown in Figure 2. An ejector lever 54 secured to the shaft 52 is extended into operative engagement with the cam 46 that has a hump 55 properly formed and located to actuate the ejector at proper times to eject formed structures from the benders and formers, the ejector extending forward from the shaft 52 into a position between the main benders and formers and to overlie the bent and formed structures when they are engaged with said benders and formers, and as illustrated in Figure 5 of the drawings.

65 Retainers 56 are secured to the under side

of the housing 13, the ends of these retainers being recessed to receive the ends of the structures as they are bent around the formers at the ends of the ribs 26, in a manner to be hereinafter described, and thereby holding the 70 structures in engagement with the main benders and formers during the bending and forming operation.

The mops 34 are supplied to the ends of feed levers 57—58, in any suitable manner, 75 either mechanically or manually, the ends of said levers being recessed to receive the ends 33 of the mops. These levers are secured at their lower ends to a rock shaft 59 mounted in bearings in brackets 60 secured to one of 80 the cross bars 11. The feed lever 57 is engaged, intermediate its ends, with a feed cam 61. The levers 50—54—57 are moved in one direction in opposition to the cams, or, in other words, are held in engagement with the 85 cams by suitable springs, as shown in dotted lines in Figure 1 of the drawings, said springs, however, being omitted in other views for the sake of clearness of the showing.

In the operation of the machine the parts being in the positions indicated especially in Figures 1, 6, 8 and 9, the levers 57—58 are operated to place the ends of a mop 34 against the pins 32 opposite the space between the 90 bending nose 31 and said pins, as clearly shown in Figure 9. The arms 47 are now actuated through the connected shafts, levers and cams, hereinbefore described, to move the shafts 29 upwardly, the pins 32 retreating into their recesses in this movement, as hereinbefore described. The ends of the mops are thus placed in the space between the studs 27 and the former ribs 26. The racks 37 are now actuated by the levers 43 and 44 100 and their connections with the cam 46 to rotate the end benders to bend the ends 33 around the formers at the ends of the ribs 26, in which movement said ends are carried into the retainers 56 and held thereby, as 105 hereinbefore described. The shafts 29 are now operated to withdraw the end benders and the mop structure is thus held in contact with the main benders and former by the 110 retainers 56.

The rack 39 is now actuated by the lever 40 and its cam 41 to rotate the gears 14 and 15 whereby, through the connections hereinbefore described, the actuating arms 18 are swung in opposite directions to move the bending arms 24 from the positions shown in Figure 6 to the positions shown in Figure 7, in which movements the blocks 17 and 21 travel along the slots in which they are located, the relative positions of the different parts at different stages in the bending operations being shown in Figures 5, 6 and 7, Figure 5 showing the initial relative location of the parts, Figure 6 the relative location of the parts after the ends have been 125 130

bent, and Figure 7 the relative location just after the final bending movement of the parts. When the bending movement is completed the ejector 51 is operated by the lever 54 and hump 55 to dislodge the formed structure from the forming devices and the rack 39 is thereafter moved in an opposite direction to return the parts to their normal positions.

10 In the forming of the main part of the mop structure the wire or body is carried around the studs 27 as said studs are moved toward each other, and this movement is permitted by reason of the sliding bearings 17 and 21 of the stud 19 and shaft 20, as hereinbefore described.

15 In accordance with the provisions of the patent statutes I have described the principles of operation of my invention, together with the device which I now consider to represent the best embodiment thereof; but I desire to have it understood that the device shown is only illustrative and that the invention may be carried out by other means 20 and applied to uses other than those above set out.

I claim—

1. A bending machine including a bending member rotatably mounted, a pair of formers projecting from said bending member and spaced for the reception of articles to be bent between them, means for operating said bending member to cause one of said formers to bend said articles around the other of said formers, a placer to place opposite ends of articles simultaneously between said formers, and means for supplying articles to said placer.

2. A bending machine including a receiving member having a former around which articles to be formed are bent, a placer for the reception of articles to be bent, means for operating said placer to deliver opposite ends of articles simultaneously to said receiving member, and means for independently operating said receiving member to bend articles about said former.

3. A bending machine including a receiving member having a former around which articles to be formed are bent, a second former projecting from said member in spaced relation to the other former, a placer having a space for the reception of articles to be bent, means for operating opposite ends of said placer to deliver said articles simultaneously into the space in said receiving member, and means for operating said receiving member to form said articles.

4. A bending machine including a receiving member having a former around which articles to be formed are bent, a second former projecting from said member in spaced relation to the other former, a placer having a bending member and a positioning member arranged in spaced relation, means for op-

erating said placer to deliver articles to said receiving member, means for operating said placer to bend articles around a former on said receiving member, and means for operating said receiving member to bend articles around the other of said formers.

5. A bending machine including a receiving member having a former around which articles to be bent are formed, a second former projecting from said bending member in spaced relation to the other former, a placer having a bending member movable on the arc of a circle defined by the axis of one of said formers to bend said articles around said former, and means for operating said placer to bend said articles as specified.

6. A bending machine including a receiving member having a former around which articles to be bent are formed, a second former projecting from said member in spaced relation to the other former, a placer having a bending member movable on the arc of a circle defined by the axis of one of said formers to bend said articles around said former, means for moving said placer longitudinally of its axis to deliver articles to said formers, and means for operating said placer to bend said articles as specified.

7. A bending machine including a receiving member having a former around which articles to be bent are formed, a second former projecting from said member in spaced relation to the other former, a placer having a bending member movable on the arc of a circle defined by the axis of one of said formers to bend said articles around said former, means for moving said placer to deliver said articles to said formers, means for operating said placer to bend said articles around one of said formers, and means for operating said receiving member to bend said articles around the other of said formers.

8. A bending machine including a receiving member having a former around which articles to be bent are formed, a second former projecting from said member in spaced relation to the other former, a rotatably mounted placer having a bending member projecting therefrom, the axis of said placer being coincident with one of said formers, and in line therewith, means for operating said placer to deliver articles to said formers, and means for operating said placer to bend said articles around one of said formers.

9. A bending machine including a receiving member rotatably mounted and having a former around which articles to be formed are bent, said former projecting in line with the axis of said receiving member, a former projecting from said receiving member in spaced relation to the first mentioned former, a placer rotatably mounted with its axis in line with one of said formers, means for moving said placer to deliver articles to said receiving member, means for operating said

- placer to bend articles about one of said formers, and means for afterward rotating said receiving member to cause one of said formers to bend said articles around the other of said formers.
10. A bending machine including a receiving member having a former around which articles to be formed are bent, a placer having a retractible positioning member arranged in line with said former, means for operating said placer to deliver opposite ends of articles simultaneously to said receiving member, and means for operating said receiving member to bend articles around said former.
11. A bending machine including a receiving member having a former around which articles to be formed are bent, a placer having a retractible positioning member and a bending member located in spaced relation to receive articles to be formed therebetween, means for moving said placer toward said receiving member to deliver said articles to said receiving member, whereby said retractible positioning member is retracted to permit bending of said article, and means for operating said placer and thereby said bending member to bend articles around said former.
12. A bending machine including a receiving member having two formers around which articles to be formed are bent, a placer having a retractible positioning member and a bending member located in spaced relation to receive therebetween articles to be formed, means for moving said placer toward said receiving member to deliver said articles to said receiving member whereby said retractible positioning member is retracted to permit bending of said articles, means for operating said placer and thereby said bending member to form articles around one of said formers, and means for operating said receiving member to bend articles around the other of said formers.
13. A bending machine including a bending member rotatably mounted, a sliding member to support said bending member, formers projecting from said bending member, a shiftable block operatively connected with said sliding member to impart oscillating movement to said bending member, means for imparting oscillating movement to said shiftable block, and means for causing reciprocating movement of said supporting member.
14. A bending machine including a bending member rotatably mounted and having formers projecting therefrom, a sliding support for said bending member having a pinion mounted on the axis of the latter, a rack meshing with said pinion, a shiftable member operatively connected with said sliding support, and means for imparting oscillating movement to said shiftable member to trans-
- mit oscillating movement to said bending member and sliding movement to said support.
15. A bending machine including a rotatably mounted bending member, a pair of formers projecting from said bending member and between which articles to be bent are received, means for rotating said bending member to cause one of said formers to bend said articles around the other of said formers, and a retainer rigidly positioned to receive a bent portion of said article passed into engagement with the retainer in the bending operation.
16. A bending machine including a receiving member having a former around which articles to be formed are bent, a placer having means to receive articles to be bent, a retainer positioned for the reception of a bent portion of said article, and means for operating said placer to bend said article around said former and to enter it into said retainer.
17. A bending machine including a receiving member having a former around which articles to be formed are bent, a placer for the reception of articles to be bent, a retainer positioned to receive a portion of said bent article, means for operating the placer to bend the article around said former and enter it in said retainer, and means for operating the receiving member to impart further bends to said article and to remove it from said retainer.
18. A bending machine including a receiving member having a pair of spaced formers, a placer for the reception of articles to be bent, a retainer positioned to receive a portion of a bent article, means for operating the placer to bend an article around one of said formers and enter it in said retainer, and means for rotating said receiving member to remove the article from said retainer and to bend it around one of said formers.
19. A bending machine including a receiving member having a former around which articles to be formed are bent, a placer having a bending member located out of line with said former and arranged to receive articles to be bent, means for moving said placer and to place said bending member in cooperative relation with said former, and means for operating said placer to bend an article around said former.
20. A bending machine including a receiving member having a former around which articles to be formed are bent, a placer for the reception of articles to be bent, means for operating said placer to deliver articles to said receiving member, means for operating said placer to bend articles around said former, means for removing said placer, and means for operating said receiving member to impart further bending movement to said articles.

GEORGE FRANKLYN MATTESON.
